UNITED STATES PATENT OFFICE.

WILLIAM LOVE THOMPSON, OF GREENVILLE, MISSISSIPPI.

PRINTING-MACHINE.

1,331,597.

Specification of Letters Patent. Patented Feb. 24, 1920.

Original application filed February 26, 1919, Serial No. 279,315. Divided and this application filed June 30, 1919. Serial No. 307,542.

To all whom it may concern:

Be it known that I, WILLIAM LOVE THOMPSON, a citizen of the United States, and a resident of Greenville, in the county of Washington and State of Mississippi, have invented new and useful Improvements in Printing-Machines, of which the following is a specification.

This invention relates to printing machines and has particular reference to that class of printing machines adapted to be used in printing the names and addresses of consignees upon shipping-tags.

An important object of the invention is to provide in a machine of the above named character a novel means for quickly selecting and setting up the several type characters composing a desired name or address.

A further object of the invention is to provide a novel automatic means for bringing a plurality of predetermined selected type selectively into position whereby they may be quickly transferred to their respective positions within the machine.

Another object is to provide a novel automatic means for successively feeding a plurality of tags to the machine and removing them therefrom subsequent to the printing operation.

A further object is to provide a novel automatic means for intermittently supplying a suitable printing fluid to the type or printing characters employed.

Another object is to provide a machine of the character mentioned, having its various coöperating elements so constructed and arranged with respect to each other as to insure accuracy and reliability during the operation of the machine.

Other objects and advantages of the invention will be apparent during the course of the following description taken in connection with the accompanying drawings.

This application is a division of my application filed February 26, 1919, for printing machines, Serial Number 279,315.

In the drawings, forming a part of this specification and in which like numerals are employed to designate like parts throughout the same,

Figure 1 is an end elevation of the machine embodying my invention,

Fig. 2 is a top plan view of the same,

Fig. 3 is a transverse sectional view taken substantially on line 3—3 of Fig. 2,

Fig. 4 is a perspective view of a guide,

Fig. 5 is a perspective view of a tag feeding and ejecting mechanism,

Fig. 6 is a top plan view of the tag feeding and ejecting mechanism,

Fig. 7 is an edge elevation of a type plate,

Fig. 8 is a top plan view of a type plate,

Fig. 9 is a top plan view of a type inserting tool,

Fig. 10 is an edge elevation of the tool,

Fig. 11 is a face view of a tag with which the machine embodying my invention is particularly adapted to be used, and,

Fig. 12 is an edge elevation of the tag.

In the drawings, wherein for the purpose of illustration is shown a preferred form of my invention, the numeral 10 indicates a base carrying an upright frame member 11 and a supporting member 44 having secured between their upper ends a head 12. I prefer to construct the base 10 hollow as shown in Fig. 3 in order to receive therein a coil spring 13 from which power to operate the machine as will hereinafter be more fully described is derived. The spring 13 is secured at one end to the base 10 as shown at 14, its other end being secured to a vertically arranged shaft 15 one end of which is journaled in the base 10 as shown at 16, 85 while its other end is journaled within a bracket 17 carried by the frame member 11. To the upper end of the shaft 15 there is fixedly secured a bevel gear 18 meshing with a second bevel gear 19 carried by a shaft 20. 90 In actual practice I prefer to maintain a ratio of two to one between gears 18 and 19 so that one revolution of the shaft 15 will cause the shaft 20 to rotate through two complete revolutions. The shaft 20 is suitably journaled within the frame member 11 as clearly shown in Fig. 3 and carries at its outer end a type wheel indicated as a whole by the numeral 21. In order to render the type wheel 21 as light in weight as possible 100 I prefer to form therein a relatively large circular groove as shown at 22. The type wheel 21 is provided with a plurality of T-shaped type slots 23 adapted to receive loosely therein a plurality of type 24. For 105 each type slot or row of type I provide a reciprocating plunger 25 one end of which is enlarged as shown at 26 and normally seated

within a chamber 27. To the outer end of the plunger 25 is secured a head 28 provided with a character as shown at 29, which character corresponds with the characters 5 of the type 24 carried by its adjacent type slot. To the outer end of the shaft 20 there is detachably secured a crank 30, this crank being adapted to rotate the shaft 15 through the gears 18 and 19 as is apparent, to wind 10 the spring 13 from which power is derived for operating the various coöperating elements as will be hereinafter more fully described.

As a means for preventing excessive speed 15 of rotation of the wheel 21 I prefer to employ a brake mechanism indicated as a whole at 31. This brake mechanism comprises a plunger 32 seated within a slot 33, the plunger 32 being free to reciprocate therein 20 and having its outer end normally engaging the inner face of the wheel 21. A slot 34 is provided within the plunger 32 and adapted to receive therein a tapered key 35. By forcing the key inwardly it is apparent that 25 the plunger 32 will be forced downwardly against the face of the wheel. During the operation of the device as the tension of the spring 13 is released the tapered pin 35 may be gradually withdrawn to partially relieve 30 the braking effect of the plunger 32 upon the face of the wheel 21. In practice it might be found that a different form of brake is more suitably adapted for this purpose than that which I have shown and described herein, the braking mechanism shown and described herein being intended only as an illustrative showing. By releasing the pressure of the plunger 32 upon the face of the wheel 21 as the tension of the spring 13 is 35 gradually decreased I am enabled to govern the speed of rotation of the wheel 21 during the type setting-up operation or the printing operation as will be more fully appreciated when considering the hereinafter described 40 operation of the device as a whole.

The upright frame member 11 is provided with a groove as indicated at 36, this groove being adapted to receive the ends of the plungers 25 when they are pushed or projected inwardly to serve as a means coöperating with certain other elements to be hereinafter described to stop the wheel 21 at predetermined points. Within the upright frame member 11 there is pivotally mounted 55 a plunger releasing lever 37, this lever being pivotally connected with the frame member 11 as shown at 38. At substantially right-angle to the lever 37 there is disposed a latch stop 39 which is pivotally connected to 60 the machine as a whole as shown at 40. The latch stop extends substantially to the outer face of the frame member 11 as clearly shown and is provided with an upright arm 41 extending an appreciable distance upwardly into a relatively large opening in the

frame member 11 as shown at 42. As a means for retaining the plunger releasing lever 37 and the latch stop 39 in their normal respective positions as shown in Fig. 3 there is provided a coil spring 43 having 70 one end connected to the latch stop 39 and its other end to the plunger operating lever 37 as clearly shown in Fig. 3.

Between the upright member 11 and the supporting member 44 there are journaled a 75 pair of removable ink ribbons carrying spools 45 and 46 carrying inking ribbon 47 adapted to be intermittently moved as will be hereinafter described. Upon pins 48 and 49 there are journaled respectively ratchet 80 wheels 50 and 51. The pins 48 and 49 are provided respectively with tapered ends 52 and 53 adapted to enter depressions carried in the ends of the spools, which depressions are arranged centrally within the ends of 85 the spools as is apparent. The ratchet wheels are provided with locking pins 54 and 55 adapted to enter depressions carried by the spools 45 and 46 respectively. These pins are, as is apparent, adapted to lock the 90 ratchet wheels against rotation with respect to the rollers or vice versa when the spools are being rotated through the instrumentality of the ratchet wheels 50 and 51. The spools 45 and 46 are provided at their other 95 ends with depressions 55 and 56 respectively which are adapted to receive the ends of plungers 57 and 58, these plungers being urged inwardly by means of coil springs 59 as clearly shown in Fig. 2. It will be noted 100 that each of the plungers is provided with a head 60 normally seated flush with the face of the depending member 44 within a counterbore 61. The heads 60 are inset in order to prevent interference with the feeding 105 of the tags during the printing operation as will more fully be appreciated upon further study of the drawings taken in connection with the specification and described operation of the machine. The inking ribbon 47 110 as clearly shown in Fig. 1 passes over a pair of guide rollers 62 which are journaled between the upright member 11 and the supporting member 44. These rollers are adapted to be removed and are provided at 115 one end with spring pressed plungers 63, these plungers being substantially identical to the plungers 57 and 58 hereinbefore described.

Within the head 12 there is slidably 120 mounted an operating plunger 64 provided with a head 65. This plunger is normally retained in the position shown in Fig. 3 by means of a coil spring 66 having its lower end arranged within a chamber 67 and its 125 upper end engaging a collar 68. To the lower end of the plunger 64 there is connected a stamping head 69, the stamping head carrying upon its upright face a bracket 70 to which is pivotally connected 130

a pawl 71 adapted to engage the teeth of the ratchet wheels 50 and 51. In the position shown in Fig. 1 the pawl 71 is adapted to engage the teeth of ratchet wheel 51 to rotate the spool 46 in such a direction as to cause a winding up of the inking ribbon 47 upon the spool 46, the inking ribbon being at the same time unwound from the spool 45. In the position of the pawl 71, shown in Fig. 1, the movement of this pawl is limited by a stationary pin 72 and a removable pin 73. By removing the pin 73 and swinging the pawl 71 about its pivotal connection as an axis to its position shown by the dotted line in Fig. 1, the reverse movement of the ratchet wheels 50 and 51 is brought about during the operation of the device, the ribbon 47 being wound upon the spool 45 and at the same time unwound from spool 46. In this position the movement of the pawl 71 is limited by a stationary pin 72' identical with that shown at 72 and the removable pin 73.

For retaining as a unit certain type necessary in the printing of a consignee's name and address I propose to employ type carrying plates such as is indicated by the numeral 74. Each of these plates is provided with slots 75, one of the slots being used to retain the type of a given name, the other being employed to retain the type of a given address. Each of the plates 74 is further provided with a beveled end as shown at 76 which, as is apparent, functions together with a thumb screw 77 to retain a given plate in printing position within the printing head 69. As a co-operating element for the type carrying plate 74, when placed in printing position within the printing head 69, I employ a detachable bed plate 78 seated within an elongated channel or seat 79, the bed plate being adapted to be inserted into the channel from the left of the table 80 which is supported in part by the upright member 11 and a suitable housing 81 carried by the base 10. The bed plate 78 is substantially identical with the type carrying plate 74 in so far as length and thickness is concerned but differs materially in that no type slots are provided therein. It often happens that a shipper has one or more customers to whom it is desired to ship material frequently and in such cases it is found desirable to retain type plates having the type always set up for the printing of the names and addresses of such regular customers in order to save time and expedite the matter of addressing tags. In such cases it is only necessary to remove the type carrying plate 74 from the head 69 and insert another having the desired name and address already set up. When it is desired to set up the type necessary to the names and addresses of consignees to whom shipments are not so frequently made, the bed

plate 78 is removed from its seat and a type carrying plate 74 substituted therefor. The type carrying plate is moved into the channel 79 until the slot 75, adapted to receive the type necessary to the consignee's name, 70 is brought into registration with a type channel 83 provided in the upright member 11, the type channel 83 being adapted to receive printing type 24 from the type slots 23 of the wheel 21 in the setting-up of type. 75 When the type necessary to the consignee's name has been set up the type carrying plate 74 is moved farther into the channel 79 until the slot 75 adapted to receive the type necessary to the consignee's address is brought 80 into registration with the channel 83 through which type from the wheel 21 is moved into the registering slot. When the type necessary to the name and address has been set up within the type carrying plate 74 it is 85 removed from the channel 79 and inserted into the printing head 69 and locked therein by the thumb screw 77. Before the printing operation is executed, however, the bed plate 78 is inserted into the channel 79 from 90 which the type carrying plate 74 has been removed.

To the end of the shaft 20 there is securely fixed a bevel gear 84 meshing with a bevel gear 85 carried by a shaft 86 suitably journaled within the end of the bracket 17. In actual practice I prefer to maintain a ratio of four to one between gears 84 and 85 so that one quarter of a revolution of gear 84 will cause a complete rotation of shaft 86. 100 To the lower end of shaft 86 there is connected a disk 87 to which is pivotally connected a pitman 88, the pivotal connection being shown at 89. The pitman 88 is adapted to actuate a card feeding mechanism indicated as a whole by the numeral 90. The card feeding mechanism comprises an arcuate-shaped track 91 secured as clearly shown in Fig. 6 to the housing 81. Upon the track 91 there is mounted a movable 105 arcuate-shaped base 92. Between the base 92 and track 91 are interposed bearings 93 which are intended to reduce the friction of the feeding mechanism to a minimum during its operation. The base 92 carries an elongated arm 94 which is pivotally connected to a vertical support 95 secured to the base 10 as clearly shown in Fig. 5. The arm is further provided with a second arm 96 which is bent downwardly as shown at 97 110 and again bent horizontally as shown at 98, the horizontally bent portion being pivotally connected as shown at 99 to the pitman 88. To the vertical support 95 and above the arm 94 there is pivotally connected a second arm 100 which is retained in a normal position by means of a leaf spring 101 secured to the arm 94 as shown at 102. The arm 100 is provided at its outer end with a flange 103 adapted to contact with down- 115

wardly depending fingers 104 carried by an arcuate-shaped support 105 which is linked or pivotally connected to the arcuate-shaped base 92 by means of links 106. Relatively 5 near one end of the track there is provided a pair of angularly bent stops 107 adapted to co-act with the arm 100 as will be more fully described hereinafter. Relatively near the other end of the track 91 there is provided 10 a lug 108 which is adapted also to co-act with the arm 100 in a manner herein-after more fully described. The arcuate-shaped support 105 is retained normally in its lowest position with respect to the arcuate-shaped base 92 by means of a coil spring 109 having one end connected with the base 92 and its other end connected with the support 105 as clearly shown in Fig. 5. From the support 105 rises a pair of converging 15 brackets 110 having their upright ends secured to a spacing block 111. Upon the spacing block 111 there is secured an arcuate-shaped feed bar 112 adapted to traverse an arcuate-shaped slot 113 provided within the table 80. To each end of the feed bar 20 there is connected a feed block, the feed blocks being indicated by the numerals 114 and 115 and provided with a plurality of teeth or serrations as shown at 116.

30 To the supporting member 44 there is suitably connected an upright guide 117, which guide is provided at its lower end with an angularly bent lip 118 arranged in proximity to an opening 119 afforded between the lower end of the member 44 and the upright face of the table 80. The guide bar 117 is further provided with an arcuate-shaped portion 120 carrying an arcuate-shaped tag retaining member 121 which extends over the inclined portion 81' of the housing 81. The housing 81 relatively near the arcuate-shaped slot 113 is not only inclined as shown at 81' but is depressed circularly as shown at 81".

45 To the member 44 there is secured by means of a set-screw 122 an elongated U-shaped tag guide rod 123, the free end of which is arranged co-axially with the vertical support 95 and beyond the inclined portion 81' of the housing 81 to enable a plurality of cards to be easily placed upon the rod 123 and to permit these cards to fall successively one by one from the rod subsequent to successive printing operations. As 50 a co-acting member for the guide 117 there is provided a second vertical guide 124 having its lower end angularly bent as shown at 125 and secured to a vertical adjustable bracket 126 carried by the housing 81. In 60 practice I prefer to provide an elongated slot 127 in the bracket 126 which makes possible a horizontal adjustment of the guide 124 in order to vary the space afforded between brackets 117 and 124 to readily accommodate tags of various widths.

The operation of the machine is as follows: Assuming that energy is stored within the spring 13 and a plunger 25 is in engagement with the latch-stop 39 the row of printing type carrying the first desired character 70 is then selected and its adjacent plunger is pushed inwardly so that its enlarged end 26 enters the groove 36. The plunger releasing lever 37 is then moved against the influence of spring 43 to release the engagement between the latch 39 and the enlarged end 26 75 of the plunger whereupon the wheel 21 is rotated until the plunger adjacent the selected row of printing type comes into contact with the end of the latch-stop 39 whereupon the selected row of printing type is brought into alignment with the groove 83, the groove 83 being in alignment with the selected slot of the type carrying plate 74 as hereinbefore described. By a suitable instrument 128 having a sharpened end as shown at 129 one or more of the printing type 24 may be transferred from a given groove 23 of the wheel 21 through the slot 83 and into the selected slot of the type 80 carrying plate 74. When it is desired to transfer another selected printing type to the selected groove of the type carrying plate 74 the selected plunger 25 is moved inwardly until its enlarged end 26 has entered 95 the groove 36 as above described. The plunger releasing lever 37 is then moved against the influence of the spring 43 to relieve the engagement between the latch-stop 39 and the previously selected plunger whereupon 100 the wheel 21 is rotated by the spring 13 through the instrumentality of gears 18 and 19 until the selected printing type are brought into alignment with the groove 83 and the selected groove of the type carrying 105 plate 74 as above described. These successive operations are repeated until the desired name and address or other desired matter is set up within the type carrying plate 74, whereupon the plate is withdrawn 110 from the channel 79 and placed in printing position within the printing head 69. The bed plate 78 is then placed in its normal position within the channel 79 for printing as hereinbefore set forth.

Having the type all set up and the various elements in their respective positions as described the printing of either ordinary shipping tags and similar cards, or tags such as are indicated by the numeral 130 may be begun. These tags may be the ordinary type, with the usual plain or reinforced eyelets, or they are provided with eyelets as shown in order that they may be retained upon the U-shaped tag guide rod 123. It is to be 125 understood that since the free end of the U-shaped guide rod 123 is spaced laterally from the table 80 as clearly shown in Fig. 5 that the tags may be fed on the rod and moved to the dotted line position as shown 130

in Fig. 5. The tags are retained in stacks or columns upon the guide rod 123, each having that portion upon which the name and address is to be printed disposed between guides 117 and 124. Before beginning to execute the printing operations care must be taken to push four of the plungers 25 inwardly so that their enlarged ends 26 will enter the groove 36. These four plungers must be spaced from each other a distance of ninety degrees as indicated by the arrow lines shown on the face of the wheel 21 in Fig. 1. The reason for the insertion of these four plungers and their equal spacing from each other will be more readily understood when considering the hereinafter described operation. It is to be assumed that one of the four plungers engages the end of the latch 39 before the first printing operation and it is to be assumed that the depending fingers 104 are supported by the arm 100 and that the connection between the pitman 88 and the disk 87 is at rest diametrically opposite to the position shown in Fig. 5. The printing head 69 is moved downwardly whereupon the lug 131 is brought into engagement with the arm 41 thereby depressing the latch 39 against the influence of spring 43 releasing the engagement between the enlarged end 26 of the plunger and the latch-stop 39. The hand is removed from the head 65 whereupon the head 69 returns to its normal position under the influence of the spring 66, thereby permitting the latch 39 to return to its normal position under the influence of the spring 43. By means of the brake 31 the speed of rotation of the wheel 21 is sufficiently retarded to permit the latch-stop 39 to assume its normal position shown in Fig. 3 before the wheel 21 will have moved one-fourth of a revolution. Upon the completion of the one-fourth revolution of the wheel 21 the next successive plunger 25 will have been brought into engagement with the latch-stop 39, thereby stopping the rotation of the wheel 21. By reason of the fact that a ratio of four to one is maintained between gears 85 and 84 the disk 87 will have completed one revolution in which instance the connection between the pitman 88 and the disk 87 will have moved from a point diametrically opposed to its position shown in Fig. 5 through three hundred and sixty degrees. Before the disk 87 is rotated the feed block 115 is centrally located under the lower tag of a given column of tags, the serrations 116 of this feed block being in engagement with the under face of the lower tag. Since the pitman 88 is connected to the rotating disk 87 and the arm 96 a movement of the arcuate-shaped support 105 is brought about. Upon the completion of a half revolution of the disk 87 the arcuate-shaped support is moved substantially to the position shown in Fig. 5 carrying with it the arcuate-shaped feed bar 112 whereupon the arm 100 is brought into engagement with the lug 108. Because of the engagement between arm 100 and the lug 108 the arm 100 is removed from under the arms 104 against the influence of spring 101 whereupon the support 105 under the influence of spring 109 immediately drops to a lower position until the arms 104 rest upon the upper face of the arcuate-shaped base 92. When the downward movement of the arcuate-shaped support 105 is brought about a corresponding dropping of the feed bar 112 is produced. Immediately subsequent to the lowering of support 105 the disk 87 will have completed its one-half turn whereupon the base 92 is moved backward along the track 91, thereby bringing the fingers 104 into engagement with the stops 107 whereupon the support 105 is elevated against the influence of spring 109. When the fingers 104 have moved an appreciable distance above the face of the base 92 the arm 100 will be forced under the fingers 104 by means of the spring 101, thereby retaining the feed bar 112 in an elevated position. It might be well for me to state here that the spring 101 is not so strong as spring 109, it being only sufficiently strong to move the arm 100 under the fingers 104 when they are lifted from the base 92, while the spring 109 is of sufficient strength to retain the fingers 104 firmly in engagement with the arm 100 and the face of the base 92 respectively during the feeding of the tags and the return of the feed bar 112 to a normal position. Immediately subsequent to the lifting of the feed bar 12 to its upper position the disk 87 will have completed one revolution. It will be noted from the above that the feed bar 112 is moved in an elevated position about the guide rod 123 as an axis, the guide rod 123 being coaxially arranged with the vertical support 95 while the disk 87 is completing its first half revolution. Since the feed bar 112 is moved forward in an elevated position the lowermost tag 130 of a column of tags is swung around the guide rod 123 into printing position under the printing head 69. The printing is done simultaneously with the release of engagement between the enlarged end 26 of the plunger and the latch-stop 39 and since the printing head 69 returns to its normal position immediately subsequent to printing there is no interference in the operation of the feeding mechanism by the printing head. Normally the feed block 114 is positioned directly below the tag 130 when in a printing position. Since this is true the printed tag is moved from under the printing head 69 simultaneously with and in advance of the movement of the next tag to a printing position. It is therefore apparent that the printed tag is ejected from the machine substantially to the position shown in Fig. 5.

multaneously with the movement of a blank tag to printing position. When the printed tag has been moved an appreciable distance from under the printing head its edges are 5 moved clear of the housing 81', thereby permitting the printed tag to fall or drop the guide rod 123. Immediately subsequent to the ejecting of a printed tag and the placing of a blank tag in a printing position the 10 arm 100 is removed from under the fingers 104 as hereinbefore described, thereby permitting the support 105 together with the feed bar 112 to move to a lower position under the influence of the spring 109 as hereinbefore described.

It might be found desirable in actual practice to employ a suitable clutch mechanism between the shaft 20 and the tag feeding mechanism to render the several co-operating elements thereof inoperative during the type setting-up operation. There are possibly many forms of conventional clutches particularly adapted to accomplish this end and I have therefore not attempted 20 to disclose any given or preferred form. If, however, in practice it should be deemed undesirable to employ a clutch as above mentioned the feeding of the tags may be prevented during the type setting-up operation 25 by simply lifting the column of tags upon the guide rod 125 and inserting a piece of card board or the like between the table 80 and the free end of the bottom tag, the card board being sufficiently thick to so space the lower tag from the table 80 as to prevent engagement of the feed block 115 therewith and so positioned upon the table 80 as to not interfere with the movement of the feed bar 112 or feed blocks 114 and 115.

40 It is to be understood that the form of my invention herewith shown and described is to be taken as a preferred example of the same, and that various changes in the shape, size and arrangement of parts may be resorted to without departing from the spirit 45 of the invention or the scope of the subjoined claims.

Having thus described my invention, what I claim as new and desire to secure and 50 protect by Letters Patent of the United States, is:

1. In a printing machine a rotatable type carrying element, means for automatically locking said type carrying element in a predetermined position, means for releasing said type carrying element whereupon it is automatically moved into another predetermined position, the direction of rotation of the type carrying element being the same 55 from one predetermined position to another, means for transferring selected type from said type carrying element to a type carrying plate at each successive position of said type carrying element, means for retaining 60 the type in the type carrying plate, and

means for returning said type to the above mentioned rotatable type carrying element.

2. In a printing machine having a rotatable type carrying element means for automatically locking said type carrying element in a predetermined position, means for releasing said type carrying element whereupon it is rotated automatically into another predetermined position, the direction of rotation of the type carrying element being the same from one predetermined position to another, means for controlling the speed of rotation of the type carrying element, means for transferring selected type from said type carrying element 70 to a type carrying plate at each successive position of said type carrying element, means for retaining the type in the type carrying plate, and means for returning said type to carrying position in the type carrying element.

3. In a printing machine having an automatically rotatable type carrying element, means for automatically locking said type carrying element in a predetermined position, the direction of rotation of the type carrying element being the same from one predetermined position to another, means for transferring type from said type carrying element to a type carrying plate at each 75 successive position of said type carrying element, means for releasing said type carrying element whereupon it is automatically rotated to another predetermined position, means for retaining the type in the type carrying plate, adjustable brake mechanism for controlling the speed of rotation of the type carrying element, and means for returning the type from the type carrying plate to the rotatable type carrying element.

4. In a printing machine an automatically rotative type carrying element, means for automatically positioning selected type in a predetermined position, means for transferring the type from the type carrying element to a type carrying plate upon the arrival of the type carrying element to its predetermined position, brake mechanism for controlling the speed of the type carrying element in its rotation, means for releasing the type carrying element from its predetermined position whereupon said type carrying element is automatically rotated to another predetermined position, and means for returning the type from the type carrying plate to the type carrying element.

5. In a machine, means for typesetting comprising in combination, a rotatable type carrying element, means for locking the type carrying element in a predetermined position, means for transferring selected type from the type carrying element to a type receiving plate upon the arrival of the type carrying element at a predetermined position, means for retaining the type in 100

5 said type carrying plate, means for releasing said type carrying element from locked position whereupon the type carrying element is rotated to another predetermined position, the direction of rotation of the type carrying element being the same from one predetermined position to another, adjustable 10 brake mechanism for controlling the speed of said rotatable type carrying element, and means for returning the type from the type carrying plate to the type carrying element.

15 6. In a printing machine means for typesetting comprising in combination, an automatically rotatable type carrying element, means for automatically locking the type carrying element in a predetermined position, means for transferring selected type from the type carrying element through 20 type slots to a type receiving plate at each successive position of the type carrying element, means for retaining the type in said type carrying plate, means for releasing said type carrying element from locked posi-

tion whereupon the type carrying element is 25 rotated to another predetermined position, the direction of rotation of the type carrying element from one predetermined position to another being the same, adjustable 30 brake mechanism for controlling the speed of said rotatable type carrying element, and means for returning the type from the type carrying plate to the type carrying element.

7. In a printing machine means for typesetting comprising in combination, a type 35 carrying element, means for rotating said type carrying element to successive positions, the direction of rotation of the type carrying element being the same from one position to another, means for transferring 40 selected type from the type carrying element to a type carrying plate at each successive position of the type carrying element, means for retaining the type in a type carrying plate, and means for returning 45 type to the above mentioned type carrying element.
